(57) **CLAIM**

We claim the ornamental design for a snow plow board, as shown and described.

DESCRIPTION

FIG. 1 is a perspective view of a snow plow board showing our new design;

FIG. 2 is a top plan view thereof, the bottom plan view being identical thereto except for the beveled edge on the front as shown in FIGS. 1 and 5;

FIG. 3 is a front end elevational view thereof;

FIG. 4 is a back end elevational view thereof;

FIG. 5 is a right side elevational view thereof, the elevational view of the opposing side being a mirror image thereof; and, FIG. 6 is a perspective view showing the snow plow board in use; the broken line sections depict environmental structure for illustrative purposes only and form no part of the claimed design.
